UNITED STATES PATENT OFFICE.

EUGENE W. VOGEL, OF OAK PARK, ILLINOIS, ASSIGNOR TO CHICAGO RAILWAY SIGNAL AND SUPPLY COMPANY, OF CARPENTERSVILLE, ILLINOIS, A CORPORATION OF ILLINOIS.

RAIL-EXPANDER.

1,242,395.

Specification of Letters Patent.

Patented Oct. 9, 1917.

Application filed February 19, 1915. Serial No. 9,346.

To all whom it may concern:

Be it known that I, EUGENE W. VOGEL, a citizen of the United States, residing at Oak Park, in the county of Cook and State of Illinois, have invented certain new and useful Improvements in Rail-Expanders, of which the following is a specification.

My invention relates to rail expanders and is in the nature of an improvement upon the 10 device of my co-pending application for United States Letters Patent filed April 6, 1914, Serial No. 830,089.

In the use of the rail expander shown in the application referred to, some difficulty 15 has been experienced because of the tendency of the spindle to bind in the threaded openings in the rail clamps. The device works admirably provided there is nothing to throw the rail clamps out of parallel and 20 provided the clamps are placed near enough to each other so that the spindle cannot bend under the very considerable stress to which it is subjected in expanding the rails. It frequently happens, however, that the rails 25 are a trifle out of alignment or are worn, bent, or perhaps not originally of exactly the same cross sectional configuration so that the rail clamps do not stand in perfect parallelism with each other. Under these 30 circumstances, the fact that the spindle is provided at each end with a thread makes it difficult and, in extreme cases, impossible to turn the spindle because of the binding action between the threads of the spindle 35 and the threading of the clamps. Furthermore, it is desirable to effect the separation of the rails without removing the angle bars, the bolts binding the angle bars to the webs of the rails being, in such case, merely loosened so as to allow the necessary movement 40 of the rails one with respect to the other. If the spindle, threaded at each end, is made long enough to span the angle bars it is likely to bend, unless made excessively 45 heavy under the stress necessary to separate the rails.

One of the principal objects of my present invention is to provide a rail expander, the operation of which is not hampered by 50 the slight defects which rails are likely to have as above noted; that is to say, to provide a device in which the spindle will freely turn even though the ends of the rails engaged are slightly bent out of line with each

other or are worn, or, for other reasons, are 55 not of precisely the same cross sectional configuration.

A further object of the invention is to provide a rail expanding device of the type described which will be long enough to span 60 the angle bars but in which there will be no tendency of the spindle to bind even when subjected to sufficient stress to cause it to bend slightly.

A further object of the invention is to 65 provide the clamping elements with means for taking a more intimate and reliable grip upon the rails than is possible in the form of device shown in my co-pending application.

The invention has for further objects such 70 other new and improved devices, arrangements and constructions relating to rail expanders as will be hereinafter described and claimed.

The invention is illustrated, in a preferred 75 embodiment, in the accompanying drawings wherein—

Figure 1 is a side elevation of a rail expander constructed in accordance with my 80 invention showing the device in operative engagement with two abutting rails; certain of the devices being illustrated in section, on line 1—1 of Fig. 2;

Fig. 2, an end elevation of the parts shown 85 in Fig. 1 with portions in section;

Fig. 3, a plan view of the parts shown in Fig. 1 with certain portions also in section;

Fig. 4, a perspective view of a clamping 90 jaw forming part of the device, and

Fig. 5, a section on line 5—5 of Fig. 2.

Like characters of reference designate like parts in the several figures of the drawings.

Broadly, the device comprises a pair of 95 clamping elements generally indicated at A and B, and a member C joining them and adapted, by rotation, to move them from and toward each other. At 10 and 11 are indicated two rails of a track normally connected by angle bars 12 and 13, held in place by bolts 14 and nuts 15. In Fig. 2, 16 designates the tie and 17 the spikes securing the track thereto.

Each of the rail clamping elements A and 105 B consists preferably of a yoke 18 having a jaw 19, a second jaw 20, and a screw 21 engaging a threaded opening in the jaw 20

2
and provided with a head 22 by means of which the screw may be turned, and which head bears against the end 23 of the yoke 18 opposite the jaw 19. The head 22 and the 5 end 23 are formed to make a ball and socket joint, and the jaw 20 is provided with a tongue 24 which operates in a suitable guideway 25 provided in yoke 18. This engagement is preferably a somewhat loose one so 10 that the jaw 20 may accommodate itself to rails that may be worn, bent or otherwise defective. The jaw 19 is formed with two rail contacting surfaces, one of which engages the inclined under face of the rail, 15 and the other of which bears against the side of the ball of the rail. The jaw 20 engages the diagonally opposite edge of the ball of the rail. To increase the grip of the clamping elements A and B upon their respective 20 rails, their jaws 19 and 20 are recessed and provided with hardened plates 26 and 27 respectively, which are inserted in the rail contacting surfaces of the jaws, and preferably have serrated surfaces, as seen most 25 clearly in Fig. 4. Preferably these plates are removably secured within the jaws by means of screws 28. By means of the plates 26 and 27 the friction between the elements A and B and their respective rails is greatly increased, particularly as against movement 30 of either of the elements longitudinally of its rail.

Generally indicated at C is a rotatable spindle by means of which the elements A 35 and B may be moved toward and from each other. The element A is formed with a socket 29, and the spindle is provided with a ball-shaped end 30 engaging said socket. An annular groove 31 is formed in the part 40 of the spindle C lying within element A and registering therewith is an annular groove 32 formed in element A. Engaging both grooves is a series of arcuate keys 33 which fit loosely in the respective grooves and 45 form an annular key which holds the spindle C and element A together. To facilitate the assembling of the parts, a gate 34 is provided, removably secured by screws 35 to element A, and shaped to form a portion 50 of the bed of groove 32. By removal of gate 34 the arcuate keys 33 may be inserted or withdrawn from the grooves 31 and 32. It will be seen that by reason of the fact 55 that the spindle C makes a ball and socket joint with element A, and by reason of the further fact that the keys 33 fit loosely within the channels 31 and 32, a limited amount of angular movement is possible in the spindle with relation to element A, while the 60 spindle is likewise free to rotate. Transverse apertures 36 are provided in the spindle for a bar for turning the same. A threaded aperture 37 is formed in the rail clamping element B for the threaded end 65 38 of spindle C.

Operation: It will be understood that the spindle may be made of any suitable length. However, when made long enough so that the device can span the angle bars, which construction is considered preferable, it is 70 only necessary to loosen the angle bar nuts when the rails are to be separated. The clamping elements are attached to the rails at points beyond the angle bars by screwing down the spindles 21. The jaw plates 75 27 are preferably formed on an angle greater than that between the upper surface of the head of the rail and its side surface so that the clamps will be capable of engaging rails of different sizes and contours. 80 On account of the ball and socket connection between the spindles 21 and elements 23 the jaws 20 may assume slightly different angular positions in accordance with the cross section of the rail engaged. Moreover there is a certain looseness, preferably 85 between the tongues 24 on jaws 20 and the guideways 25 so that the clamping elements will take a firm hold on the rails even though the rails be slightly bent or otherwise defective. The rails are separated by turning the spindle C. If, as often happens, the ends of the rails engaged by the clamps are a trifle out of line with each other, or are not of exactly the same contour, there is 90 no binding of the spindle in element B because of the ball and socket connection between the spindle and the other element A. The ball and socket connections between spindles 21 and the clamping elements 23, 100 allowing a certain adjustability in the hold of the clamps on the rail, also contributes to prevent any binding of the spindle in the clamping element B.

In the accompanying drawings and in the 105 foregoing description is set forth the preferred embodiment of my invention, but it is obvious that one skilled in the art may make modifications thereof without departing from the spirit of the invention. 110

I claim:

1. In a rail expander, the combination of 115 a pair of rail clamping elements, a spindle in threaded engagement with one of said elements and connected to the other element for rotation and angular movement with respect thereto, and means engaging the spindle and said other element for holding them together, comprising a key protruding from said other element and engaging an annular groove formed in the spindle. 120

2. In a rail expander, the combination of 125 a pair of rail clamping elements, a spindle in threaded engagement with one of said elements and connected to the other element for rotation and angular movement with respect thereto, and means engaging the spindle and said other element for holding them together, comprising a key member engaging registering annular grooves pro- 130

vided in the spindle and said other element respectively.

3. In a rail expander, the combination of a pair of rail clamping elements, a spindle in threaded engagement with one of said elements and connected to the other element for rotation and angular movement with respect thereto, and means engaging the spindle and said other element for holding them together, comprising a plurality of key members engaging registering annular grooves provided in the spindle and said other element respectively.

4. In a rail expander, the combination of a pair of rail clamping elements, a spindle in threaded engagement with one of said elements and connected to the other element for rotation and angular movement with respect thereto, and means engaging the spindle and said other element for holding them together, comprising a plurality of arcuate keys forming an annulus and engaging registering annular grooves provided in the spindle and said other element respectively.

5. In a rail expander, the combination of a pair of rail clamping elements, a spindle in threaded engagement with one of said elements and connected to the other element for rotation and angular movement with respect thereto, and means engaging the spindle and said other element for holding them together, comprising a plurality of removable key members engaging registering annular grooves provided in the spindle and said other element respectively.

6. In a rail expander, the combination of a pair of rail clamping elements, a spindle in threaded engagement with one of said elements and connected to the other element for rotation and angular movement with respect thereto, and means engaging the spindle and said other element for holding them together, comprising a plurality of removable arcuate key members forming an annulus and engaging registering annular grooves provided in the spindle and said other element respectively.

7. In a rail expander, the combination of a pair of rail clamping elements, a spindle connected to one of said elements by threaded engagement and to the other element by a ball and socket joint, there being registering annular grooves provided in the spindle and said other element respectively, and removable key members loosely engaging said grooves.

8. In a rail expander, the combination of a rail clamping element having a tapped aperture, a spindle in threaded engagement with said element, a second rail clamping element having a ball and socket connection with the spindle, there being an annular groove provided in the spindle registering with an annular groove formed in said second element,

key members loosely engaging said grooves, and means permitting the removal of said key members therefrom comprising a gate removably secured to said second element and containing a portion of the said annular groove thereof.

9. In a rail expander, the combination of a pair of rail clamping elements adapted to engage abutting rails transversely thereof each comprising a pair of jaws which bear against diagonally opposite edges of the ball of the rail, and a spindle interposed between said jaws having a threaded engagement with one of them, and a ball and socket engagement with the other; and a spindle interposed between said clamping elements having a threaded engagement with one clamping element and a ball and socket engagement with the other.

10. In a device for moving railroad rails in the direction of their length, the combination of a rail clamping element comprising a pair of members having angular jaws for engaging diagonally opposite edges of the head of a rail, a spindle for producing a thrust of one member toward the other, which has a threaded engagement with one of said members and a universal joint connection with the other permitting rotation and angular movement of the spindle with respect thereto; a second rail clamping element adapted to engage an adjacent rail; and a spindle lying substantially parallel and above the rails engaged for effecting a movement of one of said rail clamping elements with respect to the other which has a threaded engagement with one of said elements and a universal joint connection with the other permitting rotation and angular movement of the spindle with respect thereto.

11. In a device for moving railroad rails in the direction of their length, the combination of a pair of rail clamping elements each consisting of two members having angular jaws adapted to engage diagonally opposite edges of the head of a rail, one of said members being formed with a slideway in which the other member is loosely supported, and a spindle having a threaded connection with one of said members and a ball-and-socket engagement with the other; and a spindle arranged between said rail clamping elements above and substantially parallel to the rails engaged having a threaded connection with one of said elements and a ball-and-socket engagement with the other element.

12. In a device for separating the ends of adjacent railroad rails, a pair of clamps extending above the rails and adapted to grasp the rails, a spindle interposed between the clamps for separating them, said spindle having a threaded connection with one clamp and engaging the other clamp with its end,

and means for permitting angular movement of the spindle with respect to the last named clamp.

13. In a device for separating the ends of adjacent railroad rails, a pair of clamps extending above the rails and adapted to grasp the rails, and a spindle located above the ball of the rail and interposed between the clamps for separating them, said spindle engaging with its end a socket in the inner face of one clamp and having a threaded connection with the other clamp.

14. In a device for separating the ends of adjacent railroad rails, a pair of clamps adapted to grasp the rails, one clamp having a socket in its inner face located above the ball of the rail, and a spindle engaging said socket with one end and having a threaded connection with the other clamp.

EUGENE W. VOGEL.
